ATTORNEY

UNITED STATES PATENT OFFICE.

JAMES CHANDLER DARST, OF PORTSMOUTH, VIRGINIA, ASSIGNOR OF ONE-THIRD TO
ROBERT B. PRESTON, OF PORTSMOUTH, VIRGINIA.

TRAFFIC-CONTROL CROSSING WARNING.

Application filed February 8, 1924. Serial No. 691,536.

To all whom it may concern:

Be it known that I, JAMES C. DARST, a citizen of the United States, residing at Portsmouth, in the county of Norfolk and 5 State of Virginia, have invented certain new and useful Improvements in Traffic-Control Crossing Warnings, of which the following is a specification.

The invention resides in the provision of 10 a new and improved traffic crossing warning, so constructed and positioned at railroad crossings, tangent or curved, as to warn approaching motorists of the danger thereof and to so control the traffic thereover as 15 to render accidents very improbable.

It is the object of the invention to provide a control warning of the character stated wherein is embodied a means for first 20 warning the approaching motorists of the position and danger of the railroad crossing, and other means for so controlling the traffic over the roadway and across the railroad crossing as to restrict traffic to a respective side of the road, thus preventing 25 one motorist from cutting around the machine of another motorist thereby blocking traffic from the opposite direction and causing accident in this manner. Means is also provided for deterring crossing of the railroad at high speeds.

With the above and other objects in view the invention further resides in those novel details of construction, combination and arrangement of parts, all of which will be 35 first fully described, then be particularly pointed out in the appended claims, reference being had to the accompanying drawings, in which:

Figure 1 is a somewhat diagrammatic 40 plan view of the invention.

Figure 2 is a longitudinal section thereof taken on the line 2--2 on Figure 1.

Figure 3 is a somewhat enlarged cross section of the road-bed illustrating one of 45 the entrance ends of the invention.

Figure 4 is an enlarged plan view of one end of the invention.

In the drawings, in which like numerals of reference indicate like parts in all of 50 the figures, 1 indicates the roadway and 2 the rails of the crossing railroad, the ties thereof being indicated at 3.

At suitable positions at a substantial distance from the railroad crossing, and at op-

posite sides thereof, are positioned corner 55 posts 4 and 5, a set being positioned at opposite sides of the roadway at each side of the railroad, as is clearly illustrated in Figure 1 of the drawings. These posts may be constructed of any suitable material such as wood, iron, steel, concrete or the like. Between each set of corner posts 4-5 is positioned center post 6 and these center posts are joined by a raised curbing 7 extending centerally longitudinally of the 60 road-bed therebetween and being provided with suitable cut out portions 8 to permit passage of a train over the rails 2. By reason of thus projecting and positioning the curbing 7, the roadway between the posts 6 is divided into a right hand traffic side and a left hand traffic side, one divided from the other by the said curbing and serving to prevent the machines from passing one 70 around the other and thus causing them to 75 pass along slowly in a single line of traffic.

Obviously the right hand side of the road, according to the direction of travel, will be the entrance at either end of the control 80 warning, and that side of each of the posts 6 is extended, as is also the cooperating one of the posts 4, in the manner indicated in Figure 3 of the drawing; these inwardly extended foot portions cooperating with the barricade saddle 9 positioned intermediate 85 of the posts 4 and 6 and in position for deterring the speeding of a motorist into and through the entrance, by the reason of the fact that relatively small passages 10 are left between the said saddle and the 90 extensions of the posts.

It will be observed that the extended part of each post 6 serves as a supporting means for a supplemental post 11, upon which and upon the face of the cooperating post 95 4 is mounted a reflecto-type lamp 12 having a green lens to designate to the approaching motorist the entrance passage which he is to use.

It will be observed that the exit from the 100 control warning, provided for traffic coming in the opposite direction, is clear of obstruction by the posts 6 and the respective post 5 cooperating therewith in providing the exit, see the left side of Figure 3, and 105 is provided with reflecting lamps 13 having red reflecting lamps to distinguish this exit from the entrance and to contrast the re-

lection of the green lights to warn the motorist that he is not to enter that side of the road.

The approach side of the posts 5 and 6 bounding each exit may be provided with lamps 13^a of the reflecto-type having green lens to signal to the approaching motorist that the exit is clear.

It should be understood that while I have described the use of lamps of the reflecto-type, that is, such as include reflecting plates of the desired color and capable of reflecting any rays of light cast upon the same, such as those of the sun or the headlights of an oncoming motor vehicle, any accepted type of signal lamps may be used. Reflecto-type lamps are commonly used on our roadways today and, as they, per se, are no part of the present invention, further description is thought unnecessary.

As an additional signalling means for guiding the motorist and preventing him from entering that side of the road closed to traffic, or in other words, the side which acts as an exit for the traffic coming in the opposite direction, I provide an archway system 14 which may be constructed of tubing of suitable material and supported and projected vertically from the posts 4, 5 and 6. This piping serves to provide separate entrance and exit arches, the one on the right of the roadway being indicated as an entrance archway by the sign 15 suspended therefrom, and the one at the left of the roadway being provided with a sign 16 marked "Closed" to clearly indicate to the motorist that he is not to enter the archway, the sign supplementing the effect of the red lights. These archway systems may be painted in some bright color to attract the motorists' attention.

I provide a suitable passage over the railroad crossing in the nature of a road-bed composed of a plurality of planking 17 extended crosswise of the roadway between the rails and being supported upon the supports 18 which may be carried by the ties.

From the foregoing description, it will be apparent that as a line of motorists approaching the control warning their attention would be attracted by the archways and the red and green lights and the traffic would naturally be directed through the restricted entrance at the right side of the road and guided in a single continuous slow traveling line through the control warning and across the railroad crossing in safety, the longitudinal curbing preventing any motorists in the line of traffic from cutting around motorists in front of him and thereby tending to obstruct traffic coming in the opposite direction with the attendant probability of accident.

While my invention has been especially

designed and adapted for roads crossing railroads and the like, or cross roads, it is obvious that it may also be employed upon straightway roads as over the crest of hills, for example, or it may be used on curved roads where there are no crossings.

From the foregoing description, taken in connection with the drawings, it is thought that the novel details of construction, advantages and manner of use of my invention will be readily apparent to those skilled in the art to which it relates.

What I claim is:

1. In a traffic control crossing warning, the combination with the road-bed and the portion of the railroad crossing the same, of a central curbing adapted to divide the road-bed into separate traffic lanes for oppositely moving traffic and extending a distance from the railroad at either side, and barricade saddles cooperative with the divided lanes for reducing the speed of motorists through the entrance thereof.

2. In a traffic control crossing warning, the combination with a road-bed and the portion of the railroad crossing the same, of a central curbing adapted to divide the road-bed into separate traffic lanes for oppositely moving traffic and extending a distance from the railroad at their side, each said lane having an entrance and an exit, poles marking the entrances and exits, and foot extensions on the poles and barricade saddles for restricting each entrance to deter speeding of a vehicle therethrough.

3. In a traffic control crossing warning, the combination with the road-bed and the portion of the railroad crossing the same, of a central curbing adapted to divide the road-bed into separate traffic lanes for oppositely moving traffic and extending a distance from the railroad at either side, each said lane having an entrance and an exit, poles marking the entrance and exits, and barricade saddles cooperating with the entrance marking poles in restricting the said entrances to deter speeding of vehicles therethrough.

4. In a traffic control crossing warning, the combination with the road-bed and the portion of the railroad crossing the same, of a central curbing adapted to divide the road-bed into separate traffic lanes for oppositely moving traffic and extending a distance from the railroad at either side, each side lane having an entrance and an exit, poles marking the entrance and exits, barricade saddles cooperating with the entrance marking poles in restricting the said entrances to deter speeding of vehicles therethrough, archways defining the entrances and the axis, indicia carried by the arches, the poles and the barricade saddles for warning and instructing the drivers of approaching vehicles, and signal devices on the poles for warning and

- directing the drivers of approaching vehicles.
5. In a traffic crossing warning, the combination with the road-bed and the portion of the railroad crossing the same, of a central curbing adapted to divide the road-bed into separate traffic lanes for oppositely moving traffic and extending a distance from the railroad at either side, each side lane having an entrance and an exit, poles marking the entrances and exits, barricade saddles cooperating with the entrance marking poles in restricting the said entrances to deter speeding of vehicles therethrough, archways supported by the poles and defining the entrances and the exits, indicia carried by the arches, the poles and the barricade saddles for warning and instructing the drivers of approaching vehicles, and signal devices on the poles for warning and directing the drivers of approaching vehicles.
6. In a traffic control crossing warning, the combination with a road-bed and the portion of the railroad crossing the same, of a central straight line curbing dividing the road-bed into two straight and separate traffic lanes for opposing moving traffic and extending a distance from the railroad at either side, barriers at the entrance end of the traffic lanes for restricting the wheel passage of the motor vehicles to reduce the speed of motorists therethrough.
7. In a traffic control crossing warning, the combination with the road-bed and the portion of the railroad crossing the same, of a central straight line curbing adapted to divide the road-bed into separate parallel straight traffic lanes for opposing moving traffic and extending a distance from the railroad at either side, and means cooperative with the lanes for restricting the wheel passage-way of motor vehicles at the entrance to the traffic lanes, substantially as shown and described.
8. In a traffic control crossing warning, the combination with the cross-road, of a straight line central curbing adapted to divide one road-bed into separate parallel straight traffic lanes for opposing moving traffic and extending a distance from the other road-bed at either side, barriers on the road-beds in the divided lanes, said barriers being spaced apart to present narrow wheel-passages between the same whereby the speed of the motorists approaching the same must be reduced for the purposes specified.
9. In a traffic control warning, the combination with a road-bed, of a central line curbing dividing the road-bed into two separate traffic lanes for opposing moving traffic, barriers at the entrance end of the traffic lanes for restricting the wheel passage of the motor vehicles to reduce the speed of motorists therethrough.
10. In a traffic control warning, the combination with a road-bed, of a central line curbing dividing the road-bed into two parallel separate traffic lanes for opposing moving traffic, and means cooperative with the lanes for restricting the wheel passage-way of motor vehicles at the entrance to the traffic lanes, substantially as shown and described.
11. In a traffic control warning, the combination with a road-bed, of a central line curbing dividing the road-bed into two parallel separate traffic lanes for opposing moving traffic, means cooperative with the lanes for restricting the wheel passage-way of motor vehicles at the entrance to the traffic lanes, said last named means comprising barriers on the road-bed in the divided lanes, said barriers being spaced apart to present narrow wheel passages between the same whereby the speed of the motorists approaching the same must be reduced substantially as specified.
12. In a traffic control warning, the combination with a road-bed, of a central curbing adapted to divide the road-bed into separate traffic lanes for oppositely moving traffic, each side lane having an entrance and an exit, poles marking the entrances and exits, barricade saddles cooperating with the entrance marking poles in restricting the said entrances to deter speeding of vehicles therethrough, archways defining the entrances and the exits, indicia carried by the arches, the poles and barricade saddles for warning and instructing the drivers of approaching vehicles, and signal devices on the poles for warning and directing the drivers of approaching vehicles.

JAMES CHANDLER DARST.
